UNITED STATES PATENT OFFICE.

LOUIS TROLLE, OF RACINE, WISCONSIN, ASSIGNOR TO EUGENE WRIGHT LAWTON, OF RACINE, WISCONSIN.

FOOTWEAR.

1,386,637.

Specification of Letters Patent.

Patented Aug. 9, 1921.

Application filed June 5, 1920. Serial No. 386,895.

To all whom it may concern:

Be it known that I, LOUIS TROLLE, a citizen of the United States, and residing at Racine, in the county of Racine and State 5 of Wisconsin, have invented a new and Improved Footwear, of which the following is a specification.

This invention relates to the construction 10 of footwear such as boots and shoes and particularly to such as are intended for the use of miners, railway men, foundrymen, quarrymen, coke oven tenders, furnace men and others who walk among cinders, broken stone and other rough materials and on wet 15 ground in which such rough materials are embedded, and its object is to provide a flanged metal bottom to resist the wear, leather or reinforced rubber uppers extending down within the side flanges of the bottom, and a marginal reinforcing strip to 20 prevent the fasteners which secure the uppers to the bottom from being pulled through the uppers.

In the accompanying drawing, Figure 1 25 is a side elevation of a rubber boot provided with a metal bottom. Fig. 2 is a section on the line 2—2 of Fig. 1 on a larger scale. Fig. 3 is a section on the line 3—3 showing a fastener in position. Fig. 4 is a side elevation of a shoe provided with a metal bottom. Fig. 5 is a section on the line 5—5 of Fig. 4.

Similar reference characters refer to like 30 parts throughout the several views.

The combination of a sheet metal bottom 35 to resist wear and rubber or leather uppers, together with a removable hair-felt insole constitutes a comfortable foot covering which resists a maximum of wear. These 40 boots and shoes are warm in winter and cool in summer and the felt insoles can be taken out and washed so that the foot may be kept fresh and clean. But hitherto, the manufacturers of footwear of this character have 45 experienced great difficulty in preventing the bottoms from separating from the uppers, and the solution of this difficulty constitutes the present invention.

The boot shown in Figs. 1, 2 and 3 50 comprises a metal bottom consisting of a sole 1 and side flanges 2, the uppers consisting of a layer 3 of rubber thickened along its lower edge 4 which may be provided with a layer 5 of fibrous reinforcement, and the inner

lining 6, preferably a layer of fabric indurated with rubber, and a strip of leather 7 which extends entirely around the bottom of the uppers. This strip of leather is secured in position preferably by and during the vulcanizing of the rubber. 55 60

The rubber 3, lining 6 and leather 7 all extend down to the sole 1, and are secured together and to each other by means of the fasteners 8 which extend through the side flanges 2 and the layers 3, 6 and 7 and are 65 clenched back into these layers. By stopping the lower edges of the uppers and of the reinforcing strips at the metal sole, all undesirable ribs and other projections are avoided while full strength is retained. The 70 fasteners are placed so near together that the outer surface of the rubber layer 3 is closely drawn against the flanges 2 so as to render the joint water tight.

Within the foot of the boot is an insole 75 10, preferably of hair-felt which spaces the foot of the wearer from the metal sole and so prevents the foot from being chilled in cold weather and from being burned when stepping on hot cinders and slag. A heel 11 80 of any desired character may be attached to the metal bottom.

When water-tightness is not a prime consideration, a shoe 12 may be constructed with leather uppers 13 which are reinforced at 85 their lower edges by means of strips 14 of leather secured to the uppers by rows of stitches 15. The bottom has the metal sole 16 with side flanges 17 to which the uppers are attached by means of the clenched fasteners 18. These uppers again extend down to the metal sole. The bottom of the shoe may be provided with an insulating block or pad 19 which may be positioned by the sheet metal holder 20, the holder being secured to 90 the sole in any desired manner, preferably by welding. An insole 21 is again provided to insulate the foot of the wearer from the metal sole 16, and a heel 22 of any desired character may be attached to the sole. 95 100

Instead of the uppers 13 of the shoes being of leather, they may be of heavy canvas or duck material, and the reinforcing strips 7 and 14 may also be of heavy canvas or of fiber, either in natural condition or 105 properly treated as may be found desirable.

The sizes and proportions of the various parts may all be changed by those skilled in

the art without departing from the spirit of my invention as set forth in the following claims.

I claim:

- 5 1. In an article of footwear, the combination of a sheet metal bottom comprising a sole and an upright flange along the edge thereof, an upper extending down within the flange of the bottom, a reinforcing strip 10 of leather extending along the inner side of the lower edge of the upper, and clenched fasteners extending through the flange, upper and reinforcing strip.
- 15 2. In an article of footwear, the combination of a sheet metal bottom comprising a sole and an upright flange along the edge thereof, an upper extending down within the flange of the bottom and consisting of

a rubber outer layer and an inner layer of fabric, and a strip of leather between said 20 layers extending along their lower edges and vulcanized thereto, and clenched fasteners extending through the metal flange, the upper and the reinforcing strip.

3. In an article of footwear, the combination of a sheet metal bottom comprising a sole and an upright flange along the edge thereof, an upper extending down within the flange of the bottom, a reinforcing strip 25 of leather extending along the inner side of the lower edge of the upper and attached thereto, clenched fasteners extending through the flange, upper and reinforcing strip, and an insole of felt upon the metal sole.

LOUIS TROLLE.
